[57] CLAIM

The ornamental design for a personal computer, as shown and described.

DESCRIPTION

FIG. 1 is a front top and right side perspective view of a personal computer showing my new design;
FIG. 2 is a front elevational view thereof on an enlarged scale;

FIG. 3 is a rear elevational view thereof on an enlarged scale;

FIG. 4 is a top plan view thereof on an enlarged scale;
FIG. 5 is a bottom plan view thereof on an enlarged scale;

FIG. 6 is a left side elevational view thereof on an enlarged scale;

FIG. 7 is a right side elevational view thereof on an enlarged scale;

FIG. 8 is an enlarged cross-sectional view taken along line VIII—VIII of FIG. 2, the interior construction is omitted;

FIG. 9 is a front, top and right side perspective view thereof, the display window being in the closed position and the carrying handle being extended.
